(57) **CLAIM**

The ornamental design for an HVAC control device, as shown and described.

DESCRIPTION

FIG. 1 is a front elevational view of an HVAC control device showing our new design;

FIG. 2 is a rear elevational view thereof;

FIG. 3 is a top plan view thereof;

FIG. 4 is a bottom plan view thereof;

FIG. 5 is a left side elevational view thereof;

FIG. 6 is a right side elevational view thereof;

FIG. 7 is a top, front and side perspective view thereof, and FIG. 8 is front, bottom and side view perspective view thereof;

FIG. 9 is a front elevational view of the HVAC control device with opened front;

FIG. 10 is a top, front and partial side view with opened front

FIG. 11 is a side front and bottom perspective view with opened front;

FIG. 12 is a front elevational view of a second embodiment of the HVAC control device;

FIG. 13 is a rear elevational view of thereof;

FIG. 14 is a top plan view thereof;

FIG. 15 is a bottom plan view thereof;

FIG. 16 is a left side elevational view thereof;

FIG. 17 is a right side elevational view thereof;

FIG. 18 is a top, front and side perspective perspective view thereof;

FIG. 19 is a side, front and bottom perspective view thereof;

FIG. 20 is a front elevational view with an opened front;

FIG. 21 is a top, front and partial side perspective view thereof, with an opened front; and,

FIG. 22 is a side, bottom front perspective view thereof, with an opened front.
